ADJUSTABLE COMPRESSION CHAMBER

Filed July 18, 1930

FIG 1

FIG 2

INVENTOR.

Guy R. Poyer

P. F. Funk ATTORNEY.

UNITED STATES PATENT OFFICE

GUY R. POYER, OF WICHITA, KANSAS

ADJUSTABLE COMPRESSION CHAMBER

Application filed July 18, 1930. Serial No. 468,755.

This invention relates to adjustable compression chambers for internal combustion engines and the primary object of the invention is to vary the size of the compression and combustion chamber of an internal combustion engine for a piston having a fixed amplitude of movement so that the compression of the motor fuel in the combustion chamber can be varied without changing the stroke of the piston.

The novelty of the invention will be understood by reference to the following description in connection with the accompanying drawing in which:

Fig. 1 is a vertical, longitudinal, sectional view through a compression and combustion chamber constructed in accordance with my invention and

Fig. 2 is a cross-sectional view through the casing or block to which the compression chamber is secured.

The casing or block consists of two complementary members 1 and 2 to make a split block, secured together by transverse bolts 3 and 4. At suitable intervals in the block are cylinder-receiving openings 5 within which the cylinders may be secured. I have shown only one cylinder 6 although the number of cylinders may be varied. Each cylinder is provided with a threaded skirt 7 to engage the threads 8 in the portion of the block surrounding the opening 5. Within each cylinder is a piston 9 having the usual connecting rod 10 fastened to a pin or crank shaft 11 as the case may be. There are three connecting rods 10 shown for a three cylinder engine, but obviously, I do not wish to be limited to the exact number of cylinders.

Adjustable on the cylinder 6 is a head 12 having intake and exhaust ports 13 and 14 with appropriate valves not shown. The head is provided with a cylindrical skirt or sleeve 15, preferably cast integral therewith and threaded on the outer wall of the cylinder 6 as indicated at 16. The head and its skirt are provided with cooling fins 17 of appropriate construction.

For low compression engines, the cylinder 6 will be adjusted in the opening 5 away

chamber will be relatively large. Therefore, the piston will not compress the charge to as many atmospheres as it would if the combustion chamber or compression chamber happened to be smaller.

If it is desired to have high compression, the cylinder 6 will be moved inwardly toward the element 11 to bring the head nearer the piston to thus reduce the size of the compression chamber. Therefore, on the compression stroke of piston 9, the charge will be compressed to a higher number of atmospheres than in the example previously given. The adjustment can be made by loosening the bolts 3 and 4, moving the cylinder to the desired position and then tightening the bolts to cause the half-round portions of the members 1 and 2 to bind against the outside of the cylinder 6 to hold it in place and in the adjusted position.

From the foregoing it will be apparent that the cylinder may be adjusted longitudinally with respect to the piston so as to vary the size of the compression chamber, that is, vary the distance between the head and the piston at the end of the compression stroke of the piston to thereby raise or lower the compression of the engine.

According to my invention, I can make the cylinder member 6 of seamless tubing which may be threaded externally from end to end and then cut in appropriate lengths for installation in the engine block. The threads in the members 1 and 2, the threads on the cylinder member 6 and the threads on the sleeve 15 can all be cut to the same pitch. Therefore, the assembly may be built up in an inexpensive and convenient manner.

What I claim and desire to secure by Letters Patent is:

1. In an internal combustion engine, a cylinder member comprising seamless tubing provided with exterior threads from end to end, a cast cylinder head having a threaded skirt screwed on to the cylinder member and means for adjustably engaging the exterior threads of the cylinder member to fasten it to the engine block.

2. An internal combustion engine, a cylinder member provided with exterior threads

from end to end, a cylinder head having a threaded skirt screwed on the cylinder member and means for adjustably engaging the exterior threads of the cylinder member to 5 fasten it to the engine block.

3. In an internal combustion engine, a split block, a cylinder member comprising seamless tubing provided with exterior threads from end to end, a cast cylinder head having 10 a threaded skirt screwed on to the cylinder member and means for clamping the split portion of the block to the threads of the cylinder.

In testimony whereof I affix my signature.
15 GUY R. POYER.
